UNITED STATES PATENT OFFICE.

EDWARD DAVIS AND WALTER E. HOLLAND, OF PHILADELPHIA, PENNSYLVANIA,
ASSIGNORS TO PHILADELPHIA STORAGE BATTERY COMPANY, OF PHILADEL-
PHIA, PENNSYLVANIA, A CORPORATION OF PENNSYLVANIA.

DESIGN FOR A BATTERY-CASE.

59,200.

Specification for Design.

Patented Oct. 4, 1921.

Application filed May 31, 1921. Serial No. 473,918. Term of patent 14 years.

To all whom it may concern:

Be it known that we, EDWARD DAVIS and WALTER E. HOLLAND, citizens of the United States, residing in Philadelphia, Pennsylvania, have invented the new, original, and ornamental Design for a Battery-Case, of which the following is a specification, reference being had to the accompanying drawings, in which—

Figure 1 is a perspective view of a battery case illustrating our design; and

Fig. 2 is an elevation of that side of the battery case which is not shown in Fig. 1, in which the central crossing ribs have been omitted to form an open space for lettering.

We claim:

The ornamental design for a battery case, as shown.

EDWARD DAVIS.
WALTER E. HOLLAND.
